MEANS FOR ELEVATING FLUIDS

Application filed October 30, 1929. Serial No. 403,429.

This invention relates to means for elevating fluids. More particularly, the device is adaptable for increasing the production of oil from an oil well. The device contemplates the provision of a fluid pressure displacement pump which is adaptable for use in deep wells, wells with low fluid level, and where water is being produced in association with the oil.

10 This invention is not to be confused with that method of lifting a fluid, known as the gas lift, for the reason that the ordinary gas lift is restricted in its application, and more often than not, causes an emulsifying action

15 and is only capable of assisting in the lifting of a fluid a determined distance. The ordinary gas lift has many disadvantages in addition to the disadvantages just mentioned, such as retarding the production of the well

20 by a back pressure on the fluid or upon the oil sands.

The present invention provides a simple method as well as a means whereby all the disadvantages of the gas lift method heretofore mentioned are effectively overcome in an inexpensive manner and in such a manner that the said means is directly controlled by the fluid entering the well and in a natural manner rather than in an artificial manner.

30 The invention includes among its several objects the provision of a method and means whereby gas pressures on the fluid in the well are effectively eliminated with resultingly increased production.

35 Another object is the provision of a means and method of the character indicated, whereby the gas to oil ratio in a well is lowered by reducing the volume of circulated gas.

Another object is the provision of a device

40 of the character stated which does not produce an aerated column in the fluid, hence eliminating bad emulsions.

Another object is the provision of a device in which any gas within the well formation is

45 conserved, and utilized to give an increased ultimate yield.

Another object is the provision of means adapted to give a steady production flow of the fluid in that the gas entry into the fluid

50 tubing is automatically controlled without

the use of artificially controlled devices at the surface of the well to the end that a continuous production of the fluid is assured and loss of producing time is eliminated.

Another object of the invention is the provision of a method and means for increasing the production of the fluid in a well by decreased elevating costs, in that group well pumping is permitted, thereby eliminating endless trouble and expense incidental to the sucker rod method of pumping.

Briefly stated, the method and means about to be described utilizes a fluid valve and a gas valve so coupled that when the fluid valve is elevated, the gas valve is closed, and vice versa, with the result that when fluid enters the well tubing and finally reaches its static level, the fluid valve closes automatically under the effects of gravity and gas pressure, the gas valve then opening and allowing gas to force the fluid from the tubing. The gas thereafter expands and in so doing, the pressure is reduced so that the fluid will again enter through the fluid valve and this action will, prior to its passage through the fluid valve, close the gas valve, and the cycle of operation is again repeated. Due to the fact that the gas only comes in contact with the bottom of the column of fluid, an aerated column is not produced. Therefore, the fluid is elevated from the well in its natural state or as it flows into the well, thus eliminating many of the problems encountered in producing fluid from wet wells.

85 A gas anchor can be used with this method of pumping and by having it of a suitable length to meet the conditions of the well, the production can be made from a low enough depth in the fluid to insure holding back the formation gas, thereby prolonging the life of the well and giving a higher ultimate yield.

During the past few years, there have been developed wells of great depths. When the flush production has been delivered from these wells and the gas pressure declines, serious problems face the operators. The straight gas lift cannot be used at great depths for the pressure that it would take to

lift the oil would also put back pressure on the sands and prevent the fluid from entering the well. A sucker rod pump is out of the question at great depths for the lifting load would be so great that it would be impractical to attempt to develop a rod that would stand up under such a strain and, furthermore, wells of great depth are often crooked so that the rods would cut out the tubing in a short time. The present invention, however, solves the deep well pumping problem, in that the method and means to be described works as efficiently in a shallow well as it does in a well of depth.

15 Other objects will be set forth as the specification proceeds, and with the object of providing a method and means for pumping fluids which is simple of construction, efficient in operation, and generally superior, 20 the invention consists in the novel and useful provision, formation, construction, association and relative arrangement of parts, members and features, as well as the method of using the same, all of which means are shown 25 in the several embodiments in the accompanying drawings, described generally and more particularly pointed out in the claims.

In the drawings:

Figure 1 is an elevation, partly in section, 30 of an oil well incorporating the invention, Figure 2 is an enlarged fragmentary vertical sectional view of a portion of the invention,

Figure 3 is a view similar to Figure 2, certain parts thereof being in changed relation,

Figure 4 is an elevation of a portion of the invention,

Figure 5 is a sectional view on the line 5—5 of Figure 4,

40 Figure 6 is a cross sectional view on the line 6—6 of Figure 3,

Figure 7 is a cross sectional view on the line 7—7 of Figure 3,

Figure 8 is a vertical sectional elevation of 45 a slightly modified form of the invention,

Figure 9 is an elevation partly in section of a length of casing incorporating a packer,

Figure 10 is a continuation of Figure 9 and showing a portion of the invention, and,

50 Figure 11 is a vertical sectional elevation of a double pipe installation where the casing will not permit a packer to be run.

Referring to the drawings, the form of the invention depicted in Figures 1 to 7, inclusive, is designated as an entirely by A, and the same includes a liquid inlet valve a, a gas inlet valve b, a displacement chamber member c within which are the members a and b, pump tubing d through which liquid is elevated, and a pressure line member e, as well as sundry pressure and liquid control means f at the surface of the well, all of which elements may be utilized in practicing an embodiment of the invention.

55 The elements a, b and c taken as a group,

provide what may be termed as a fluid pressure displacement pump which, in a measure is controlled both by fluid flowing into the well hole and gas pressure directed thereto from the surface of the well.

70 Referring to Figures 1 and 2, 1 indicates the surface of the well and 2 the well bore in the earth formation. Within this well bore is a casing 3 forming one element of

75 the pressure line e. This casing extends downwardly within the formation and adjacent the bottom of the well hole. A casing or tubing head is provided at 4 and suitable valved controlled lines 5 and 6 connect with

80 this head and have communication with the interior of the said casing. Within the said casing is the pump tubing d and this tubing also connects with the tubing or casing head and a valved controlled line 7 is in direct

85 communication therewith. The fluid pressure displacement pump is usually so placed with relation to the oil sands and the oil that would ordinarily rise within the casing 3

90 that the same is submerged, preferably to a depth such that the static pressure head of the oil which would normally be above the pump is substantially equal to the gas pressure which would be directed upon the gas

95 line. This condition is illustrated in Figure 1, the level of the oil being at 8. However, as will hereinafter appear, oil will not rise around the pump after a "kick over" due to the presence of a packer below said

100 pump, although in certain installations, it may not be necessary to use the packer. The displacement chamber member c includes a substantially annular casing 9 provided with

105 end couplings 10 and 11, the coupling 10 being of the reducer type and being in screw-threaded engagement with the end of the pump tubing d, as shown at 12. The portion

110 of largest diameter of the coupling is internally screw-threaded for screw-threaded engagement with the casing 9, as shown at 13, and the reducer coupling 11 is likewise inter-

115 nationally screw-threaded at 14 for engagement with the opposite end of said casing 9 and externally screw-threaded at 15, whereby a perforated screen 16 may be secured thereto.

The coupling 10 is provided with a central internal gas inlet line 17 having branches 18 communicating exteriorly of the said coupling.

Furthermore, the said coupling 10 is externally screw-threaded and shoul-

120 dered at 19 whereby the end of a screen 20 may be secured thereto, the upper end of the screen being bent inwardly at 21 for close engagement with the periphery of the tubing d. The gas pressure valve is adapted

125 to be secured to the line 17. The gas inlet valve b includes a valve housing 22 formed with interrupted central bores 23, 23a. These bores act as seat portions for a piston

130 valve 24. The piston valve includes a cylindrical member formed with a central bore 25

adapted to receive therein a member 26, which member is provided with a central bore 27 and with a transverse bore 28 in communication with the central bore. A pair of branch ducts 29 in the member 24 communicate with the central bore 27 and with the base of the valve 24. It will be noted that the transverse bore 28 is positioned above an end of the member 24. The housing 22 is provided with one or more enlargements 30. These enlargements take the form of cages in that the same are formed with slots 31 and adapted to confine ball valves 32, which ball valves control communication between the said slots 31 and a central chamber 33. As before stated, the central bore 23, 23a is interrupted and this interruption is due to the presence of the chamber 33. The housing 22 is secured to the line 17 by screw-threading or the like, as shown at 34. Furthermore, the said housing is internally screw-threaded at 35.

The fluid valve *a* includes a cage 36, the head 37 of which is externally screw-threaded for engagement with the threads 35 of the housing 22, and this said head is provided with a central bore 38. The cage 36 is adapted to have screw-threaded thereto an annular valve seat member 39. Adapted for reciprocal movement relative to the seat and the cage is a valve 40 and which valve is directly connected to a stem 41, which stem forms an extension of the valve 24, the said stem being passed through the central bore 38 of the head 37. This valve 40 is formed with a conical shaped head 42 and with an annular shoulder portion 43. To limit upward movement of the valve in one direction, the cage is shouldered at 44, so as to be in a position to strike the annular flange member 43, and movement downwardly of the valve is stopped by the said flange striking the top of the seat 39. The casing 9 is internally threaded at 45 and in screw-threaded engagement with said threads in an annular shouldered nut 46, the shoulder portion of which is adapted to bear against the end of the cage 36 and the annular seat member 39, and act as a supporting member therefor. The nut 46 is provided with one or more kerfs 47 whereby the said nut may be turned by a suitable tool.

As before stated, a screen 16 is screw-threaded to the threads 15 and the screen in turn is externally screw-threaded at 48 for screw-threaded engagement with an annular packer 49. This packer is illustrative only as a packer of the type shown at 125 in Figure 9 would probably be used. This packer spans the gap between the casing 3 and the said screen. Thus, fluid under ordinary circumstances is forced to enter through the screen and within the end of the coupling 11 rather than by being permitted to pass up-

wardly between said coupling and the casing 3.

The form of the invention illustrated in Figure 8 is designated as an entirety by B, the operation of this form of the invention being the same as the form A, and inasmuch as many of the elements are the same, like references will be applied wherever possible. The chief difference in construction between the forms A and B resides in the gas inlet valve *g* and the construction of the cage of the liquid inlet valve *h* for the form B; otherwise the elements are the same. The gas inlet valve includes a valve casing 50 formed on the head of the cage 51 of the liquid inlet valve *h*. The upper end of the casing is externally screw-threaded at 52 for cooperation with the screw-threads 34 of the inlet line 17. Slidable within the bore 53 of the casing is a piston valve including a cylindrical element 54 formed with a central bore at 55 and provided with one or more ducts 56 communicating with said central bore. A plug 57 has screw-threaded engagement with the upper end of the member 54 and said plug is provided with a central bore 58 and likewise with a tip 59 provided with a transverse bore 60 communicating with the bore 58. The tipped portion of the plug is adapted to extend beyond the upper limits of the member 53. Adapted to be confined in the bore 55 beneath the plug 57 is fibrous material, such as steel wool, 61. This member 54 is formed with a stem 62, which has direct connection with the valve 40. The casing 50 is formed with an annular external flange 53, and the casing is provided with one or more transverse ports 64 located immediately below the said flange. The annular member 65 is provided with an annular shoulder 66, and this member is adapted to surround the periphery of that portion of the casing 50 above the flange 63 and to have the shoulder portion 66 thereof resting upon said flange. Furthermore, this member is provided with an annular skirting 67 which is spaced from the periphery of the casing and particularly that portion of the casing in the zone of the ports 64. This construction provides an annular space 68 between the periphery of one portion of the casing and the interior surface of the skirting, which annular space is in direct communication with the ports 64. It will be noted that the member 65 shoulders against an end of the member 17 when the said member 65 surrounds in part the casing 50.

Referring to Figures 9 and 10, I have shown one form of installation of the improved pump wherein a packer 125 is placed above the perforated casing 126 and between the casings 127 and 128. This packer is of conventional form and adapted to seal off the space so that oil or other fluid cannot escape past the packer. The casing 128 corresponds to the casing 3 as shown in Figures 1 and 2,

and within the said casing is the pump tubing d . A screen 129 is coupled to the casing 128 and the screen in turn may be directly coupled to another casing which is connected 5 to a reducer collar 130. This reducer collar connects with a further length of tubing 131 corresponding to the pump tubing d . A packer or seal-off ring 132 is interposed between the screen and the tubing d . A collar 10 133 may be secured to the upper end of the tubing d , and bear upon suitable packing 134, resting upon the ring 132. Thus, the weight of the tubing is maintained by the collar resting upon the packing and the ring 15 132. As shown, the casing 128 is secured to the threads 19 of the member 10 of the pump. It will be seen that any oil or other fluid entering the perforations of the screen 126 will have to move downwardly in order to pass 20 through the screen 16 and up the pump tubing d and that the gas under pressure at the surface of the well is passed downwardly between the casings 127 and 128, through the screen 129, into the space included between 25 the pump tubing d and the casing 128, and thence into the branches 18 of the gas inlet line 17.

In Figure 11, I have shown an arrangement which is adapted for use in a well where 30 the outer casing 135 has become broken or bent or suffered other damage so that it is impracticable to direct gas down between said casing and a casing 136. In this instance, the casing 136 may extend to the surface of 35 the well. The usual pump tubing d is within the confines of the casing 136. Gas under pressure would then flow between the casing 136 and the tubing d and through the screen 20.

40 The operation, uses and advantages of the invention just described are as follows:

Taking the form of the invention designated as an entirety by A and assuming that it is to be placed within a well, the pump 45 along with the tubing is lowered within the well casing to the desired depth. A packer is, of course, included and lowered with the pump. If oil is standing in the well casing, it is evident that this oil will completely 50 immerse the pump and surround the pump tubing substantially as shown in Figure 1 at 8, the surface 8 indicating the height to which the oil has risen in the casing, or its so-called static level. It now becomes essential 55 to "pack-off" a zone beneath the pump and the packer is then brought into action for this purpose. Roughly, as before stated, the member 49 illustrates the packer, although the form shown in Figure 9 at 125 60 would probably be used for this purpose. It is essential for the type of the invention shown in Figure 1 to remove the oil from the space included between the pump tubing d and the casing 3. In order to do this, 65 the well may be swabbed, or if excessive gas

pressure is not necessary, the fluid between the tube d and the casing 3 may be forced downwardly through the screen 20 into the branches 18, line 17, opening the ball check valves and upwardly through the pipe d . This is conveniently done by opening the valve 5, closing the valves 6, 100 and 102, and opening the valves 7 and 101. The valve 5 communicates with the source of gas pressure. The valve a would, of course, be 70 closed and the gas pressure valve b would be open or, in other words, the valve members of the pump would be in the position illustrated in Figures 3 and 8. The form of the invention illustrated in Figure 8 overcomes 75 certain disadvantages of the form A in that gas under pressure will raise the fluid column between the casings without the necessity of swabbing which, as has been stated, might be necessary for the form A. 80

It will be noted that the form B does not use the ball check valves and the annular space 70 acts in a measure as a gas pocket to prevent entrance of liquids therein. Furthermore, there is little liability of impairing the function of the valve elements through the presence of sand and other debris in this latter form, although it is evident that sand might rapidly cut away the ball valves of the form A. 85

It is assumed that the form B is lowered within the well casing and immersed in the oil or other fluid. This oil or other fluid will surround the pump in accordance with the showing of Figure 1. However, instead of attempting to force the fluid, such as indicated in Figure 1, back down through the branches 18 and assuming the same valve arrangement as shown in Figure 1, I may close the valve 5 leading to the gas pressure line and open the valve 6, leading to the oil sump. A by-pass 200 communicates with gas pressure line 201, and valve 5, and this particular line contains a valve 100 communicating with the fitting that connects with the tubing d . The valves 5, 101 and 102 are closed and the valves 7 and 100 are opened. Hence, gas under pressure will be directed downwardly through the tube d into the annular space 68 through the branches 18 and out through the screen to lift the oil or other fluid between the tube d and casing 3 into the casing head 4, and past valve 6 to the oil sump. After the oil has been lifted from the casing, the flow of the gas under pressure is reversed by closing the valve 100 and opening the valve 5 so that the gas flow path is between the casing 3 and the tubing d and through the branches 18; the oil in the well by this time being forced to enter the screen 16 to get past the valve 40. This is ordinarily termed a "kick over" and aids in starting operation of the well. It is, of course, understood that suitable valves must be manipulated to permit the oil to pass upward- 110 115 120 125 130

ly through the tube *d*, such as by closing the valve 6 and opening the valves 7, 101 and 102. It is intended that the gas should be separated from the oil after the oil is lifted.

5 It will be evident that in the form B, the flow path of the gas under pressure as well as the oil or other fluid to be lifted may be directed in any path desired either through the tube *d* or between the casing and the said tube.

10 Assume the parts of the valves *a* and *b* in the position shown in Figure 3, and that the pump as an entirety has been placed within the well hole in such position that the oil or 15 other fluid has a tendency to enter through the screen 16. Gas under pressure may be allowed to flow downwardly between the casing 3 and tubing *d* through screen 20 and into the line 17. This gas will then raise the ball 20 valves 32 so that the said gas escapes through the ports 31 and upwardly through the tubing *d* for the form A, and for the form B through the ports 64 and into the tubing *d*. If the condition just stated occurs, obviously 25 pressure against the fluid valve 40 would be relieved and the oil or other fluid under pressure will enter the screen 16, pass upwardly and lift the valve 40 to the position shown in

Figure 2. Before the valve 40 is completely 30 unseated to permit passage of the liquid or oil, the gas valve through the medium of the stem 41, will move said gas valve to close entrance of gas under pressure through the inlet line 17 into the displacement chamber *c*. Thus 35 the oil will rise within the displacement chamber and thence upwardly within the tubing *d*. This oil will rise until it reaches its static level whereupon the pressure of the gas directed downwardly will exert sufficient pressure 40 upon the gas valve to open it. Likewise, gravity will affect the fluid valve 40 and aid in seating the said valve. The moment the gas valve opens, gas under pressure will lift the column of fluid in the tubing. When the 45 column of fluid reaches the surface of the well, it is directed through the valve 7 and valved lines 100, 101 and 102. Due to lightening of the load, the gas starts to expand, whereupon the valve 40 will commence to open, and prior to a complete opening thereof to admit further oil or other fluid, will close the gas valve and the displacement of the column of fluid is completed by the expansion of the gas plus the pressure of the incoming 50 fluid. These displacements are continued with definite regularity as long as the fluid enters the well. Owing to the fact that the gas only comes in contact with the bottom of the column of fluid, an aerated column is not produced. A very distinct advantage of this method of lifting oil is the fact that this pump is controlled by the fluid in the well which is a natural control and not by some artificial means on the surface.

55 Referring to Figure 2, gas under pressure

may be passed through the ports 27 and 29 and into the space included between the end of the valve 25, the head 37 and the bore 23a. This construction is important for several reasons, one being that when the valve 25 is 60 in the position shown in Figure 3, it is essential that no vacuum be produced back of the valve; otherwise, it would not lift readily, and likewise to provide a means for escapage 65 of gas when the valve is moved from the position of Figure 2 to that of Figure 3. However, there is a difference in effective pressure areas between the head of the valve and that portion confined between the head 37 and the said valve, due to the cross sectional area 70 of the stem 41. Hence, the effective pressure area upon which the inlet gas acts in tending to move the valve 25 from the position of Figure 2 to the position of Figure 3 is equal to the difference in areas between the head 75 of the valve and the area of the foot less the area occupied by the stem 41. It is intended that the effective pressure area on the head 80 of the valve 25 should be such that the entire valve assemblage is positively actuated to 85 close the oil inlet valve and open the gas inlet valve, prior to the oil being elevated reaching its static level.

Actual results in the field have shown that the invention is highly efficient in operation. 90 Pumps of the character described which have been installed and in operation over a period of months in certain experimental wells are operating with definite regularity and the wells are producing from 75% to 100% more 95 fluid than they were before the installations were made. The invention is susceptible to group well pumping in that each well is taken care of automatically. When the fluid reaches a certain height in the well, the pump 100 lifts it out and automatically ceases to operate until the head is restored. These displacements will continue regularly as long as fluid comes into the well, the number per hour depending upon the depth of the well and quantity of fluid.

105 It is quite apparent that this invention is not of necessity confined to the lifting of oil in a well as it will work equally satisfactorily with other fluids, such as water.

110 While I have not shown the actual means for separating the gas from the oil after the oil has been lifted, or for that matter the plant that supplies the gas under pressure, or passage within the well, yet it is evident that this is all a matter of common expediency utilizing well known devices now on the market.

115 It is evident that the member 26 placed within the bore 25 of the piston valve may be shortened and fibrous material placed within said bore and beneath said member 26, for the purpose of collecting any débris that might be passed through the port openings 27 and 28 and to prevent such substances 120

125

from being received between the head 27 and an end of the said piston valve.

It is obvious that various changes and modifications and variations may be made in practicing the invention in departure from the particular showing of the drawings without departing from the true spirit thereof.

I claim:

1. In a fluid pressure displacement pump, 10 a displacement chamber member provided with a liquid inlet and a liquid outlet, a gas pressure conduit and a gas pressure valve joined to said conduit and controlling entrance of gas under pressure within the displacement chamber member; said gas pressure valve including a housing formed with a transverse port, a cylindrical valve member reciprocable within said housing to open and close said port, open at one end and a 15 skirting member adapted to spacedly surround said gas pressure valve housing in the zone of said transverse port.

2. In a fluid pressure displacement pump, 20 a displacement chamber member provided with a liquid inlet and a liquid outlet, a liquid controlled valve for said inlet, a gas pressure conduit and a gas pressure valve joined to said conduit and controlling entrance of gas under pressure within the displacement 25 chamber member, said gas pressure valve being directly connected to the liquid control valve that the former is actuated by the latter to close the former when the latter is open and vice versa; said gas pressure valve 30 including a housing formed with a transverse port, a cylindrical valve member reciprocable within said housing to open and close said port, and a skirting member open 35 at one end adapted to spacedly surround said 40 gas pressure valve housing in the zone of said transverse port.

In testimony whereof, I have signed my name to this specification at Los Angeles, California, this 18th day of October, 1929.

45 CHARLES B. PENDLETON.
